Attorney, Agent, or Firm—Dunlap & Coddng***[57]****CLAIM**The ornamental design for a flower pot cover, as shown and
described.**DESCRIPTION**FIG. 1 is a perspective view of our new flower pot cover
design;FIG. 2 is an end elevational view, the opposite and being a
mirror image thereof;FIG. 3 is a side elevational view, the opposite end being a
mirror image thereof;

FIG. 4 is a top plan view thereof;

FIG. 5 is a bottom plan view thereof;

FIG. 6 is an end elevational view of the design of FIG. 1, the
only difference being in the horizontal angle of the skirt;FIG. 7 is an end elevational view of the design of FIG. 1 the
only difference being in the diwnward angle of the skirt;FIG. 8 is an end elevational view of the design of FIG. 1 the
only difference being in the near vertical angle of the skirt;FIG. 9 is a perspective view of a second embodiment of our
new flower pot cover design;FIG. 10 is an end elevational view, the opposite end being
a mirror image thereof;

FIG. 11 is a top plan view thereof;

FIG. 12 is a bottom plan view thereof;

FIG. 13 is an end elevational view of the design of FIG. 9,
the only difference being in the horizontal angle of the skirt;FIG. 14 is an end elevational view of the design of FIG. 9, the only difference being in the near vertical angle of the skirt;

FIG. 15 is an end elevational view of the design of FIG. 9, the only difference being in the downward angle of the skirt; FIG. 16 is a perspective view of a third embodiment of our new flower pot cover design;

FIG. 17 is an end elevational view, the opposite end being a mirror image thereof;

FIG. 18 is a top plan view thereof;

FIG. 19 is a bottom plan view thereof;

FIG. 20 is an end elevational view of the design of FIG. 16, the only difference being in the horizontal angle of the skirt;

FIG. 21 is an end elevational view of the design of FIG. 16, the only difference being in the near vertical angle of the skirt;

FIG. 22 is an end elevational view of the design of FIG. 16, the only difference being in the downward angle of the skirt; FIG. 23 is a perspective view of a fourth embodiment of our new flower pot cover design;

FIG. 24 is an end elevational view, the opposite end being a mirror image thereof;

FIG. 25 is a top plan view thereof;

FIG. 26 is a bottom plan view thereof;

FIG. 27 is a side elevational view of the design of FIG. 23, the only difference being in the horizontal angle of the skirt;

FIG. 28 is a side elevational view of the design of FIG. 23, the only difference being in the near vertical angle of the skirt;

FIG. 29 is a side elevational view of the design of FIG. 23, the only difference being in the downward angle of the skirt; FIG. 30 is a perspective view of a fifth embodiment of our new flower pot cover design;

FIG. 31 is an end elevational view, the opposite end being a mirror image thereof;

FIG. 32 is a top plan view thereof;

FIG. 33 is a bottom plan view thereof;

FIG. 34 is an end elevational view of the design of FIG. 30, the only difference being in the horizontal angle of the skirt;

FIG. 35 is an end elevational view of the design of FIG. 30, the only difference being in the near vertical angle of the skirt; and,

FIG. 36 is an end elevational view of the design of FIG. 30, the only difference being in the downward angle of the skirt. The characteristic feature of the design resides in the specific pleating arrangement, comprised of the parallel disposition of the exterior folds, in combination with the interior V-shaped folds, all as best seen in FIGS. 1, 9, 16, 23 and 30.

UNITED STATES PATENT AND TRADEMARK OFFICE
CERTIFICATE OF CORRECTION

PATENT NO. : Des. 371,322
DATED : July 2, 1996
INVENTOR(S) : Donald E. Weder et al.

It is certified that error appears in the above-identified patent and that said Letters Patent is hereby corrected as shown below:

On the title page, Item [73] Assignees: should read as follows

-- Trust International, Inc.;
Southpac Trust International, Inc., --.

Signed and Sealed this
Seventh Day of October, 1997

Attest:

BRUCE LEHMAN
